DATA HANDLING AND COMMUNICATION TERMINAL

Samuel A. Morgan, Ann Arbor, Mich., and John Svezia,
Millburn, N.J., assignors to Sycor Inc., Ann Arbor,
Mich., a corporation of Delaware

Filed Apr. 3, 1969, Ser. No. 16,573

Term of patent 14 years

Int. Cl. D14—02

U.S. Cl. D26—5

FIG. 1.

FIG. 2.

FIG. 4.

FIG. 3.

FIG. 1 is a perspective view taken from the front and top of the data handling and communication terminal embodying our new design;

FIG. 2 is an elevational view taken from the left side thereof; the right side being a mirror image of the left side shown;

FIG. 3 is another perspective view taken from the front thereof; the rear being plain and unornamented; and

FIG. 4 is a perspective view taken from the front and top of a modified form of the data handling and communication terminal shown in FIG. 1.

The broken lines in FIGS. 1, 3 and 4 indicate that the keyboard extends across the area occupied by such lines.

Our design is characterized by the features, in the overall design concept, of the narrowed width of the keyboard section relative to the remainder of the device, as well as the elongated recesses along the top and bottom edges of the projecting upper portion of the device.

We claim:

The ornamental design for a data handling and communication terminal, substantially as shown and described.
